UNITED STATES PATENT OFFICE.

HAROLD L. MYERS, OF MORRISTOWN, NEW JERSEY.

DISPLAY-BOX FILLER OR BACK.

Application filed June 8, 1925. Serial No. 35,618.

This invention relates to advertising or display devices and has particular reference to foldable cardboard or like structures that are adapted to be made readily and cheaply from a material best suited for the purpose and which is capable of being printed upon or decorated for display purposes to the best advantage.

More specifically, the invention relates to 10 a cardboard structure or the like having portions creased or scored for bending or folding and other portions so stamped or cut out as to form receptacles or keepers for articles of merchandise or other commodities, coincident with the folding or bending of the sheet or card.

Among the objects of the invention is to provide a box filler or holder in the nature of a rack having receptacles or pockets usually arranged in pairs for the holding of unit items of merchandise such as vials, pencils, lip sticks, and so on, each receptacle or pocket being so constructed as to hold the article reliably from accidental dropping or loosening from its place, but permitting it to be withdrawn or replaced when and as often as desired.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a perspective view of one form 40 of the invention, indicating the manner of formation of the blank and the beginning of the folding or shaping operation.

Fig. 1^a is a view similar to Fig. 1, but showing a slight modification.

Fig. 2 is a plan view of a complete display device according to the form of Fig. 1, but in completely folded or nested position and arranged within a container.

Figs. 3 and 4 are transverse sectional details on the corresponding lines of Fig. 2.

Fig. 5 is a plan view corresponding in nature to Fig. 2, but showing a modification of the improvement.

Fig. 6 is a perspective view of the holder

as in Fig. 5, but in partly folded position. 55

Fig. 7 is a plan view of the same in flat form.

Fig. 8 is a central sectional view of the same in the position shown in Fig. 5.

Fig. 9 is a plan or face view of another 60 modification designed especially for holding pencils or sticks of merchandise.

Figs. 10 and 11 are transverse sectional views of the same on the corresponding lines 65 of Fig. 9.

Fig. 12 is a plan view of the blank in flat form from which the device of Fig. 9 is formed, but on a reduced scale.

Referring now more specifically to the drawings the display filler or holder shown 70 in the first set of figures is made from a single sheet of material such as cardboard and so stamped as to provide a base 13 and integral pairs of fingers 14 projecting laterally in opposite directions and in the same plane as the base, the fingers and the base constituting a rigid structure or as rigid as the stock from which the device is made will warrant. Extending, however, laterally from the base are a series of strap-like 80 keepers 15. These keepers are connected to the base along hinge lines or creases 16 and are parallel to one another on each side of the base. Each finger 14 is stamped or cut from the space between a pair of the keepers 85 on the same side of the base, and because of the creases 16 the series of keepers are adapted to occupy a plane at an angle to the plane of the base and fingers. The outer ends of the keepers are connected 90 along hinge or crease lines 17 to a guard panel 18 and said guard panel is connected along another crease or hinge line 19 to a flap 20. By bringing the keepers and panel portions 18 upward or forward from the 95 plane of the base and fingers and folding the panels rearward around the hinge lines 17 and the flaps rearward and inward toward each other, the flaps may be caused to interlock between the fingers and the keepers 100 as shown best in Fig. 3, making the device to a large extent self-retained without the use of glue or special fasteners. This type of holder, however, is best adapted for use in connection with an outside container as 105 indicated at C in the nature of a rectangular box into which the foldable holder is adapted to fit.

The relative lengths of the keepers and fingers and the widths of the panels and flaps may be varied as may be desired according to the intention of the user of the article and particularly with reference to the nature of the articles to be carried or held in the box for sale or display purposes. In Figs. 1 and 2 the parts are so related that the panels 18 lie in planes oblique to the plane of the base and so as to provide for the panels to converge toward each other at their front edges whereby are produced under cut pockets 18^a into which the ends of the article such as indicated at A in Fig. 5 may project with a snapping fit. By this means the articles are held in a reliable position but with a full display of the entire article or practically the entire article, an item of great importance in the merchandising of items bearing their own distinguishing names or colors.

Fig. 1^a is a suggestion of a slight variation from the structure of Figs. 1 and 2 in that the panels 18 instead of being continuous are interrupted and are formed in sections 18^b which constitute in effect extensions of the keepers 15, the same bending lines 17 and 19 being observed as before described. The pockets or receptacles for the merchandise in this instance may lack the interlocking or under cut features, but the articles are held in place by the outer container C or its equivalent, from endwise movement, and from lateral movement by the edges of the keepers. The interlocking of the flaps 20 between the keepers and the fingers may be the same as before described.

In Figs. 5 to 8 I show an adaptation of the invention designed particularly for the subdivision of a carrier such as a box C' wherein the main space will be filled by an article such, for instance, as a razor package, while another portion thereof requires for best display purposes to be made smaller than the box otherwise would contemplate for holding a smaller package as, for instance, a package of safety razor blades indicated at B. In this form of the invention the base 13^a with its tongue or finger 14^a, lying in the same plane and rigid as before, fills the bottom of the box C'. The flap 20^a is connected as before to the base by means of keepers 15^a and is adapted to be folded or interlocked between the tongue 14^a and the keepers. The keepers in this instance are each jointed for bending or hinging at 17^a and are hinged at their ends along the lines 16^a and 19^a for the purpose above set forth. The space then left between the inner edges of the keepers 60 is made to conform to the size of the special package B so as to present the most pleasing display, and whereby the smaller package will be held in the most desirable position in the box for symmetry. It will be noted in this form as shown in Fig. 7

that, as also will be true in Fig. 1^a, a portion of the stock will be cut out at the end of the tongue or finger.

For the holding for display purposes of such articles as lead pencils, lip sticks, 70 styptic pencils, fountain pens, and numerous other analogous articles, I prefer to produce the invention in the form shown in Figs. 9 to 12 which while following the same inventive principle as already explained, is 75 one in which the locking flaps 20^b may be folded one upon the other back of the base 13^b and there glued or fastened as by eyelets 21 or their equivalent, making a rigid structure and one suitable for hanging or standing self-supported. From the blank in Fig. 12 it will be noted how the device is preferably cut, forming the fingers 14^b and 14^c, the latter of which are formed with projections 14^d which are an incident to the formation of elliptical notches 15^d in the edges of the keepers 15^e while the keepers 15^b are or may be substantially similar to those at 15 above described, although the fingers 15^b cut therefrom are shown with rounded ends. 80 The arrangement of the creases 16, 17, and 19 as well as the panels 18 and flaps 20^b is practically the same as in Figs. 1 and 2 except as to the manner of fastening the flaps already described. The formation of the keepers 15^b provides that a pronounced pocket is formed at one end of each receptacle into which the point p of an article such as a pencil P must be inserted endwise. The cylindrical opposite end of the pencil 100 will then be snapped downward past the shoulders 15^e formed at the outer end of each elliptical opening. In view of the fact that the latter mentioned end of the receptacle, the one having the elliptical opening, 105 lies at an oblique angle to the plane of the base and fingers, the pencil will lie in uniform stable position substantially flat against the base and fingers at the bottom of its receptacle and the elliptical seat for the larger 110 end thereof will conform to the rounded formation of the pencil. Thus will be provided an effective interlock for the pencil or other article while yet insuring practically complete display of the face thereof. To remove the pencil or other item from the holder the larger end thereof is grasped and drawn directly forward past or between the shoulders 15^e, and when the pencil is so released from such end of its receptacle, the 115 opposite pocket or end of the receptacle will of course, permit the point of the pencil to be withdrawn. As before stated, the relative angles between the planes of the keepers, the panels 18 if used, and the other parts of the structure may be varied in many particulars without departing from the spirit of the invention.

It will be observed that in all forms of the construction shown or suggested herein a 120

display holder of suitable design for the particular work intended may be produced with the utmost expedition and economy of material and which will prove of ample strength for the purpose set forth.

I claim:

1. A display holder comprising a base, flaps spaced laterally therefrom, and receptacle-forming pairs of strap-like keepers connected integrally with the base and extending thence to and connected with the flaps, said flaps being foldable back of the keepers, and means for holding the flaps in such position.
- 10 2. A display holder for merchandise composed of a unitary foldable sheet and comprising a flat base, a tongue projecting therefrom and in the plane thereof, a pair of parallel keepers on opposite sides of the tongue and deflected at an angle to, and extending to the plane of the base and tongue, and a flap connected to the keepers remote from the base and constituting means to fix the keepers in article-holding position.
- 15 3. A display holder as set forth in claim 2 in which the flap is interlocked between the keepers and the tongue for fixing the holding position of the keepers.
- 20 4. A display holder comprising a base, flaps spaced laterally therefrom and from each other, and receptacle-forming keepers connected integrally with the base and ex-

tending thence to and connected with the flaps, the flaps being foldable inward toward each other close to the base.

35

5. A display holder comprising a base, a tongue integral with the base and extending therefrom, a flap, and article-holding keepers having their ends integral respectively with the base and flap, the keepers being bent to bring the flap beneath the same and to lie against the tongue.

40

6. A display holder comprising a base, flaps spaced laterally therefrom, and receptacle-forming keepers connected directly with the base and extending thence to and connected with the flaps, the keepers being bent to enable the flaps to lie adjacent to said base and parallel thereto.

45

7. A display holder comprising a base, a pair of spaced keepers struck outward from the plane thereof, said keepers being bent to lie disposed at angles to the base and having other angles with vertices in spaced relation to an edge of said base, a tongue integral with the base and from which said keepers are struck, a flap extending parallel to the base and connected to the keepers in spaced relation to said vertices, said flap being so arranged as to lie underneath the keepers and against said tongue to form a re-enforcement for the base.

50

In testimony whereof I affix my signature.
HAROLD L. MYERS.
